UNITED STATES PATENT OFFICE.

JOSEPH G. NIKART, OF VIRGINIA, MINNESOTA.

LUNCH KIT.

Application filed June 12, 1922. Serial No. 567,611.

To all whom it may concern:

Be it known that I, JOSEPH G. NIKART, a citizen of Lithuania, residing at Virginia, in the county of St. Louis and State 5 of Minnesota, have invented certain new and useful Improvements in Lunch Kits, of which the following is a specification.

This invention relates to improvements in lunch kits and has for its objects to provide 10 a device wherein danger of the kit accidentally opening and expelling the contents is effectually avoided.

Another object is to provide means for 15 expelling the drawer of the kit when the same is released.

A further object of the invention is to provide a latch which will hold the draw 20 closed against the influence of opening means so as to avoid accidental opening until released by the user.

These and other analogous objects are attained by the novel design, construction and arrangement of parts hereinafter described and shown in the accompanying drawing, 25 forming an essential part of this disclosure, and in which:—

Figure 1 is a side view of a lunch kit constructed in accordance with this invention, showing portions broken away to more 30 clearly illustrate the details of construction.

Figure 2 is a vertical sectional view taken on line 2—2 of Figure 1.

Figure 3 is a fragmentary view of the 35 side of the kit showing the locking device in unlocked position.

Referring to the drawing, the numeral 10 designates the outer shell of the device which comprises a pair of parallel sides or walls 11 connected at the lower edges by a 40 bottom wall 12 and at their upper edges to a top member 13, arched as illustrated, to accommodate a thermos bottle. As shown in the drawing, the shell is closed at one end by a wall 14, while the opposite end is left 45 open and intermediate the top and bottom of the shell, is a partition 15, upon which the thermos bottle rests.

Fitted into the open end of the shell is a 50 drawer structure 16 beneath the partition 15, as illustrated in Figure 1.

The front wall 17 of the drawer structure 16 projects upwardly forming a closure for the upper portion of the shell, as will be 55 clearly seen upon reference to the drawings. Formed intermediate the upper and lower ends of the projecting portion of the front

wall 17, is a depression 18 for the reception of a plate 19 by means of which a link handle 20 is pivotally connected to the wall 17.

As shown, this handle is provided with an 60 arm 21 extending through a slot 22 formed in the bottom wall of the depression 18 and secured to the inner end of the arm is a connecting element 23, its opposite end being attached to the free end of a leaf spring 24, 65 secured as at 25, to the inwardly projecting flange 26 of the wall 17.

The free end of the spring is provided 70 with an upturned latch finger 27, adapted to engage in an opening formed in the upper wall or top member of the shell, adjacent its open end. It will thus be seen that, as the drawer structure is entered into the shell to its full extent, the finger 27 will engage in the opening and accidental removal of 75 the drawer from the shell will be prevented.

In order to further lock the drawer in the shell, there are provided in the side wall of the shell, and in the side wall of the drawer, matching openings 28, for the reception of 80 the locking tongue 29 of a suitable fastener 30.

If so desired, a compression spring 31 may be attached, as at 32, to the inner side 85 of the wall 14 in such manner that its outer end will engage the inner end of the drawer structure when the same is in place, and exert pressure thereon to aid in the removal of the drawer from the shell.

While certain preferred embodiments of 90 this device have been shown and described, it will be understood that changes in the form, arrangements, proportions, sizes and details thereof, may be made without departing from the scope of the invention as 95 defined in its broadest aspect.

Having thus described my invention, what I claim as new and desire to secure by Letters Patent, is:—

A lunch kit comprising an outer shell, a 100 container fitted into the outer shell, a handle for withdrawing the container from the outer shell, means connected with the handle and actuated upon movement thereof into withdrawing position to unlock said container within the shell, auxiliary locking means to hold the device in assembled position, and means for urging the container 105 out of the shell when the locking means is released and said handle raised.

In witness whereof I affix my signature.
JOSEPH G. NIKART.
